[57] CLAIM

The ornamental design for a forging press, as shown and described.

DESCRIPTION

FIG. 1 is a front elevational view of a forging press showing our new design, the rear being a mirror image thereof;

FIG. 2 is a right side elevational view thereof;

FIG. 3 is a left side elevational view thereof;

FIG. 4 is a top plan view thereof;

FIG. 5 is a bottom plan view thereof; and

FIG. 6 is a top right and front perspective view thereof.
